UNITED STATES PATENT OFFICE

CLARENCE L. HERROD, OF HOUSTON, MISSISSIPPI

VACUUM ELECTRIC THROTTLE

Application filed May 31, 1929. Serial No. 367,538.

My present invention has reference to a vacuum electric throttle as an attachment to gasoline motors, for the control of the motor's speed at a station distanced from the motor.

5 The primary object is to provide an attachment easily associated with a gasoline motor and adapted to function therewith in conjunction with the vacuum created in the intake manifold of the motor, whereby the 10 throttle of the motor is controlled by electrical circuits operated in harmonious conjunction with the vacuum equalizing elements of the device.

15 The device hereinafter described is especially designed as an attachment to the motor of a tractor employed as motive power to a portable saw-mill, and has as its purpose the acceleration of the speed of the saw driven by the tractor, just before the log is advanced 20 on the mill-carriage to contact with the saw; the control exercised to be by the same human agency as governing the progress of the saw carriage.

25 Various other uses and advantages of the invention will be in part more obvious from an inspection of the accompanying drawings, and will be in part more fully set forth in the following particular description of one form of the device embodying the invention.

30 In the drawings:

Figure 1 is a rear view of the invention.

Figure 2 is a front view thereof.

Figure 3 is a cross-sectional view of same.

35 Figure 4 is a cross sectional view of the needle valve control.

Figure 5 is a rear perspective view of the throttle arm, disposed to extending through the lateral sleeve in the lower portion of the housing.

40 Figure 6 is a perspective view of the control switch.

Figure 7 is an end cross sectional view of the cylinder 2 and component attachments.

45 Referring now to the drawings in detail, the numeral 1 designates the housing which is bolted to the intake manifold of a gasoline motor, the side next the manifold being that shown in Figure 1; this attachment is completed by passing bolts thru eyelets 1a and 1b in the housing, and bolting to the mani-

fold, the duct 1c in the housing being in extended relation to the intake manifold duct, on completion of the attachment.

The duct 1c leads from the intake manifold to the vacuum chamber 19 formed in 55 the housing 1.

Cylinders 2 and 2' are disposed opposite each other at either side of the housing 1. Cylinder 21 passes thru the chamber 19 connecting thereby the cylinders 2 and 2' 60 with the chamber.

A duct 23a is disposed in the top of the cylinder 21, and is adapted to retain the lower end of the rod 18 which extends thru the chamber 19 and one side of the housing 1 65 to the exterior thereof as disclosed in Figure 3. The rod 18 at its outer extremity is provided with a trip finger 8; and extending from the finger well within the block the rod is turned to make a tight fit between rod 70 and housing wall. The opening 17' in the housing 1 thru which the rod 18 passes is of one dimension, but the rod is turned down along its inner extension with the housing thus providing an open chamber connecting 75 with the vacuum chamber 19, thus the rod 18 has a certain pull inward exerted on it at all times by the vacuum maintained in the chamber 19.

Oppositely disposed to the duct 17' is a 80 duct 17 leading from the opposite side of the housing to the chamber 19.

Mounted by support elements 4a and 4a' across the top of the housing 1 is a trip-rod 4 with a semi-flexible joint 4c.

85 Viewing the device, as illustrated in Figure 3, the rod 4 passes thru a sleeve-eyelet in the arm of the valve-trip 4b. The opposite extremity of the rod 4 is U-shaped, the lower end of which is adapted to close the mouth 90 of the duct 17.

The cylinders 2 and 2' are open at either end having disposed in each the pistons 2c and 2c' on piston-rods 2b-2b' connected to the heads 2a and 2a'. Ducts 2d and 2d' extend from the ends of the pistons 2c-2c' to the inner side of each of the rods 2b and 2b'. Affixed the piston heads 2a and 2a' are flexible arms 2x and 2x', at the free ends 100 of each of said arms are the needle valve

points $2w$ and $2w'$ adapted to close the mouths of the ducts $2d$ — $2d'$.

Viewing the device as illustrated in Figure 2, the cylinders 2 — $2'$ are provided with corresponding parallel guide slots which extend from the respective outer ends of the cylinders 2 — $2'$ to about three-fourths the length of the respective cylinders, and in which move the guide posts 13 and 14 attached the heads $2a$ — $2a'$. The posts 13 and 14 are connected by a rod 12 , this rod has at its center a pin $12a$ extending laterally thereto and adapted to engage with a lever rod 15 .

A pin 16 fitted within a laterally disposed sleeve $1d$ in the housing 1 extends from the front to the rear of the housing through the sleeve $1d$, the rear extremity of this pin having disposed therein a slot $15b$ adapted to connect with the motor throttle proper. Extending at a right angle to the pin 16 and connected with the front extremity of the pin is the arm 15 provided with a U-shaped sleeve joint in which the pin $12a$ is adapted to freely move.

An adjustable stop 11 is provided on the front side of the housing 1 which stop is adapted to control the swing of the arm 15 in its movement to the right.

Coils 3 — $3'$ are mounted at either end of the housing 1 by support means 10 , said coils being suspended in a relative position above the cylinders 2 and $2'$ respectively. The support means 10 extends laterally across the inner upper side of the housing 1 , with the flange extending partially upward and over the housing 1 , as shown in Figure 1, the respective ends of the support means 10 rigidly supporting the coils 3 — $3'$ independently of the housing 1 . At the outer extremity of each coil is appended a spring blade 5 — $5'$ with adjusting screws 6 — $6'$ comprising contact elements at the free ends of the blades. The elements 6 — $6'$ are in alignment with the corresponding points $2z$ — $2z'$ on the respective piston heads $2a$ and $2a'$.

Oppositely disposed to the coils 3 — $3'$ are the contact points 7 and 8 on the rod 4 .

Cable Y extends from coil 3 to blade $5'$ and cable X extends from the coil $3'$ to the blade 5 . The cable Z extends from coil 3 to the control switch 26 and cable z' extends from coil $3'$ to a second contact point of the control switch. Battery B is grounded by cable C to the housing 1 and the cable W extends from the battery to a connection with the control switch 26 , as illustrated in Figure 6.

The control switch 26 is preferably located on the control stick of the sawmill. The switch 26 comprises a base proper 26 and lever handle 27 suspended in relation to the base by hinge 31 . The handle 27 is normally maintained in a predetermined relation to the contact control posts 28 and 30 by the spring 29 .

The needle valve 21 connecting the cylinder 2 and $2'$ with the vacuum chamber 19 is illustrated in cross-section in Figure 4 of the drawings. This valve 21 is comprised of a casing proper at either end of which are the nipples 22 — $22'$. Normally disposed within the casing 21 and between the nipples 22 — $22'$ is the valve proper 23 — 24 — 25 . A duct $23a$ leads from the vacuum chamber 19 to the interior of the sleeve valve 23 . Disposed within the sleeve valve 23 is a compression spring 25 , and between the base of the valve 23 and the needle 24 , this spring adapted to normally retain the needle 24 pressed against the mouth of the valve 23 . Ducts lead from the inner chambers of the cylinders 2 — $2'$ through the nipples 22 — $22'$, respectively, to the base of the valve 23 and needle head 24 .

In the operation of the above described device, the switch control is attached to the saw lever, and is held in the hand of the sawer. The points 28 and 30 are insulated from the base 26 . The spring 29 normally maintains the contact circuit through the point 30 .

To break this contact and make a circuit through the point 28 the lever handle 27 is pressed inward by a squeeze of the hand; this last contact makes a circuit thru coil $3'$ to ground 6 . The finger 8 is pulled outward by the magnetic circuit thru the coil $3'$ which opens the throttle; and simultaneously with the opening of the throttle the ground is broken at 6 , which breaks the current of electricity. When the handle 27 is released, the contact with the point 28 would be broken and contact with the point 30 would be made which would make an electrical circuit thru the coil 3 with the ground at the point $6'$; an electrical circuit thru coil 3 draws the trip-rod 4 to the left and thereby raising the valve trip $4b$, permitting the rod 8 to be drawn in by the vacuum thru 17 . As explained, the coils 3 and $3'$ act as magnets, so that when electrical currents are alternately passed thru them, the respective points 7 and 8 are alternately controlled.

In the operation of the valve 21 , the member 23 normally closes the duct thru 22 in to the cylinder 2 and correspondingly the member 24 does not close the duct thru $22'$. The vacuum thru member 21 and duct $22'$ into the piston $2'$ draws down the needle in the valve seat of the duct $2d'$ and correspondingly the piston $2c'$ is drawn inward by the vacuum.

The pistons $2c$ and $2c'$ being tied by the rod 12 , the piston $2c$ is moved to the left, or outwardly, and correspondingly is the associated arm 15 and member 16 , to which is attached the motor throttle, moved leftward.

To open the valve seat closed by the member 23 , and close that valve now left open by the member 24 , the finger 8 is pulled outwardly by magnetizing the coil $3'$, and the rod 18 thus shifts the valve 23 — 24 — 25 in

corresponding movement, which movement of the elements creates vacuum within the cylinder 2 drawing the piston 2c inwardly, and correspondingly moving the piston 2c' outwardly. This last described movement of the associated elements opens the throttle of the motor.

To hold the rod 18 in the last described position the trip 4b supported by the rod 4, 10 is provided. This trip is adapted to drop in front of the finger 8 and thereby hold the rod outwardly, until the trip 4b is pulled upward by the movement of the rod 4 to the left by magnetizing the coil 3.

15 When the finger 8 is released by the trip 4b it is pulled inward by vacuum thru 17', and at the same time the pistons 2c' and 2c move to the left in reverse manner to the action previously described, and thereby the throttle is closed.

Easy flexation in the movement of the bar 4 is permitted by the joint 4c.

What I claim is:

1. In a device of the class described, a 25 housing with a centrally disposed vacuum chamber therein, laterally disposed ducts extending from either side of the housing to the vacuum chamber, pistons disposed in said ducts and alternately responsive to magnetic influence, means to control the magnetic influence exerted on the pistons, and oppositely disposed pistons within the oppositely disposed cylinders on either side of the housing, the movement of the latter 30 pistons responsive to the vacuum influence exercised through intermediary conductive means.

2. In a device of the class described, a 40 housing with a centrally disposed vacuum chamber therein having a connection for an intake manifold, and laterally disposed within the chamber a vacuum conductive means adapted to control the influence of vacuum within the chambers of the oppositely disposed cylinders, and an associated means with the conductive means responsive to alternately exercise a magnetic influence.

3. In a device of the class described, a 50 housing with a centrally disposed vacuum chamber therein, and connecting with an intake manifold oppositely disposed cylinders at either side of the housing, said cylinders connected with the vacuum chamber in the housing by a laterally disposed conduit element, and disposed within the conduit element a control means responsive to vacuum influence exerted through the cylinders, and associated means with the control means responsive to independent magnetic influence, 55 and pistons disposed within the cylinders responsive to the vacuum influence within the cylinders, said pistons adapted to control the movement of a throttle rod extending to a motor.

65 4. For connection to an internal combust-

tion motor, a housing, a vacuum chamber disposed in said housing, associated means to set up a vacuum within the chamber, oppositely disposed cylinders at either side of the housing, said cylinders connected with the vacuum chamber in the housing by a laterally disposed conduit element, disposed within the conduit a control element adapted to control the influence of vacuum through the oppositely disposed cylinders, a control means associated with said control element, said control means responsive to independently controlled magnetic influence and pistons disposed within the cylinders responsive to the vacuum influence within the cylinders, 70 said pistons in movement adapted through intermediary means to control the position of a throttle rod extending to a motor.

In testimony whereof I hereunto affix my signature.
